(57) **CLAIM**

The ornamental design for a connector for a nasal cannula assembly, as shown and described.

DESCRIPTION

FIG. 1 is a front, left side and top perspective view of a connector for a nasal cannula assembly showing our new design.

FIG. 2 is a left side view thereof.

FIG. 3 is a right side view thereof.

FIG. 4 is a rear view thereof.

FIG. 5 is a front view thereof.

FIG. 6 is a top view thereof.

FIG. 7 is a bottom view thereof.

FIG. 8 is a rear, right side and top perspective view thereof; and,

FIG. 9 is a sectional view thereof taken along line 9-9 of FIG. 2.

1 Claim, 4 Drawing Sheets
